UNITED STATES PATENT OFFICE

FRANK J. DOUGLASS, OF CHICAGO, ILLINOIS, ASSIGNOR TO ELOISE KASTLER DOUGLASS,
OF CHICAGO, ILLINOIS

RADIATOR

Application filed October 19, 1928. Serial No. 313,451.

My invention is concerned with certain improvements in steam heating systems.

One of the objects of the invention is to provide means for trapping and holding in the radiators of a steam heating system any grease or scum or other matter that will float on the surface of the water of condensation which collects in the bottom of the radiator.

10. The ordinary steam radiator is made up of cast iron sections. The cores used for casting the sections contain grease and some of this grease adheres to the inner surfaces of the radiator from which it is likely to be 15. dislodged little by little after the radiator has been installed. This grease, with other foreign matters such as dirt, traces of coarse sand and the like, collects as a scum on the surface of the water of condensation 20. that accumulates in the radiator and escaping through the outlet pipe, in the case of a two-pipe system such as the ordinary vapor system, or through the common inlet and outlet pipe of a one-pipe system, causes 25 trouble and inconvenience by clogging valves and traps and particularly by forming a grease film in the boiler to which, in most cases, water of condensation is returned, the grease film interfering with the 30 vaporization of the water in the boiler. Even when the water in the boiler is drawn off for the purpose of clearing the boiler of this grease film, which invariably accumulates during the first few days' operation 35. of the heating system, the remedy is only partial. The grease collects on the walls of the boiler and when fresh water is introduced forms a new film on this body of water.

40. My invention contemplates providing a simple and inexpensive means of holding the grease scum in the radiator. So far as it escapes at all it is in very small quantities so that the harm done is minimized.

45. A further object of the invention is to provide a device of this character which can be used with the radiator of a one-pipe steam heating system; or interchangeably with the radiator of a two-pipe system. In this respect the device is an improvement

upon that patented in my Patent No. 1,592, 927 granted July 20, 1926, which device can be used only with a two-pipe system, that is at the outlet end of the radiator.

The same device serves a different and important function when used in the radiator of a one-pipe system. It acts as a deflector of the incoming steam causing the steam to rise through the end section of the radiator so that water hammer is prevented. Because of this, smaller piping may be used. This prevention of water hammer and use of smaller piping constitutes another object of the invention.

The invention is illustrated in a preferred embodiment in the accompanying drawings in which:

Fig. 1 is a fragmentary side elevation of the steam radiator of a one-pipe steam system, embodying the grease retaining device 70, of my invention.

Fig. 2 is a similar view of the radiator of a vacuum steam system showing the grease retaining device as applied at the outlet end 75 of the radiator.

Fig. 3 is a sectional perspective view of the nipple, modified in accordance with my invention, for fastening together the lower ends of the adjacent end sections of the radiator, and

Fig. 4 is a view in perspective of the grease retaining device.

Referring first to Fig. 1, 10 designates a radiator for a one pipe steam heating system consisting of a plurality of cast iron sections secured together, in the usual way, at the top and bottom of the sections. 11 designates the common supply and return pipe through which steam passes to the radiator and which receives water of condensation outflowing from the radiator, this pipe being provided ordinarily with a shutoff valve 12 connected to the end section 13 of the radiator by a short pipe section 14 and gland 15, which latter screws into an opening formed in a boss 16 on the end radiator section 13. The sections of the radiator except the end section 13 and the adjacent section 17 are secured together at the bottom with the usual externally threaded sleeves or nipples 100

18, these nipples being ordinarily formed with a pair of diametrically arranged ribs 19 for the tool used for screwing the nipples into the radiator sections; or nipples having 5 a smooth driving fit may be used.

Preferably, in carrying out my invention, I employ, for making a connection between the end section 13 and the adjacent section 17 of the radiator, a similar nipple 20, which, 10 however, is formed at the extremity which fits into the end section 13 of the radiator with a rabbet 21. This rabbet is provided so as to form a suitable seat for the grease retainer and steam deflector 22 shown in 15 enlarged perspective in Fig. 4. This device is preferably cup-shaped, consisting of a cylindrical side wall 23 and an end wall 24. After the radiator has been built up, section by section, the device 22 is put through the 20 opening which afterward receives gland 15, and is fitted tightly into the rabbet 21 of the specially formed nipple 20 which secures together the two adjacent end sections 13 and 17. The device 22, which is arranged 25 to project into and engage frictionally within the interior of the end section, is formed with an aperture 25 of considerable size and is arranged so that this aperture will be at the bottom. In order to adapt the device as grease retainer for use interchangeably in a two-pipe system, as will be described, the end wall of the cup may be formed with a small vent 26 as shown in Fig. 2. This opening performs no function 30 when the device is used in the radiator of a one-pipe system and is omitted preferably because of possible interference with the steam deflecting function of the device. In a one-pipe system, it will be understood the 35 air ordinarily escapes from the last section, (designated 27 on the drawing) through an air valve 28. The vent in any case is located high enough so that it will be above the normal level of the water in the radiator which 40 is indicated by dotted line *a—a* Fig. 1. The application of the device to a radiator of a two-pipe vacuum system is illustrated in Fig. 2. 29 designates the supply pipe, shown as provided with the usual shut-off valve 45 30. This pipe delivers steam to the upper portion of one of the end sections 31 of the radiator. 32 is the return pipe provided with a steam trap 33. The device 22 which 50 functions solely as a grease retainer, is arranged in the passageway between the end radiator section 34 and the adjacent section 35, being fitted into the nipple 20 in the same way as in the case of the radiator 55 shown in Fig. 1. The vent 26 permits the outflow from the radiator of air and of 60 enough steam to actuate the trap 33.

In both the arrangements shown in Figs. 1 and 2 the orifices 25 are below the water level in the radiator which is fixed by the 65 lower edge of the connecting pipe 14 (Fig.

1) or 36 (Fig. 2). Therefore any floating scum which collects in the radiator is retained therein, except for the small amount which comes from the walls of the end radiator sections 13 and 34. The orifice 25 70 is large enough to permit free outflow of water of condensation in the case of a two-pipe system and also inflow of steam as well as outflow of condensate in the case of a one-pipe system. The vent 26 is above the 75 normal water level in the radiator. It can be made quite small since its only function is to permit the outflow of air from the radiator and of enough steam to actuate the trap, that is in the case of a two-pipe system. It has no function in a radiator of a 80 one-pipe system.

In a one-pipe system the device 22 compels the steam entering the end radiator section 13 to rise in that section whence it is distributed to the other sections through the duct or passageway 37 at the upper end of the radiator instead of moving horizontally into and through the bottom duct or passageway connecting the radiator sections. This prevents water hammer likely to occur in the radiators of a one-pipe system due to the meeting of the incoming steam and the outflowing water of condensation. To check this it has been customary 85 to reduce the velocity of the steam by using piping of relatively large diameter. When the steam deflecting device of my invention is employed, it is possible to reduce the diameter of this piping besides eliminating 90 the possibility of water hammer.

Realizing that modifications might be made, I wish it to be understood that I intend to cover by patent all such modifications 95 within the scope of the appended claims.

By the term "heating medium" as used in the claims I intend to include both steam and water of condensation.

I claim:

1. In combination with a sectional radiator, a grease retainer arranged in the passageway between one end section of the radiator and the adjacent section, projecting into the interior of the end section and formed in the bottom with an aperture for passage of heating medium.

2. In combination with a sectional radiator, a grease retainer arranged in the passageway between one end section of the radiator and the adjacent section, projecting into the interior of the end section and formed in the bottom with an aperture for passage of heating medium and, at a point above the normal water level in the radiator, 115 with a vent.

3. In combination with a sectional radiator, a cup-like grease retainer arranged with its open end in the passageway between one end section of the radiator and the ad- 120

130

jacent section and its other end apertured on the under side and projecting into the interior of the end section of the radiator.

4. In combination with a sectional radiator, a cup-like grease retainer arranged with its open end in the passageway between one end section of the radiator and the adjacent section and its other end apertured on the under side and projecting into the interior of the end section of the radiator, said grease retainer being formed above the normal water level in the radiator with a vent.

5. In combination with the adjacent end sections of a sectional radiator, a nipple securing the lower ends of said sections together and providing a passageway between them, and a cup-like grease retainer having its open end fitted into said nipple and its other end apertured at the bottom and projecting into the interior of the end section of the radiator.

6. In combination with the adjacent end sections of a sectional radiator, a nipple securing the lower ends of said sections together and providing a passageway between them, and a cup-like grease retainer having its open end fitted into said nipple and its other end apertured at the bottom and projecting into the interior of the end section of the radiator, said grease retainer being formed above the normal water level in the radiator with a vent.

7. In combination with the adjacent end sections of a sectional radiator, a nipple securing the lower ends of said end sections together and providing a passageway between them which is formed at the extremity engaging the end radiator section with a rabbet, and a cup-like grease retainer having its open end fitted into the rabbet in said nipple and its other end apertured at the bottom and projecting into the interior of the end section of the radiator.

45 FRANK J. DOUGLASS.
